UNITED STATES PATENT OFFICE.

CHARLES P. FAY AND OSCAR F. MOSSBERG, OF CHICOPEE FALLS, MASSACHUSETTS; SAID MOSSBERG ASSIGNOR TO J. STEVENS ARMS & TOOL COMPANY, OF CHICOPEE FALLS, MASSACHUSETTS, A CORPORATION.

BREECH-LOADING FIREARM.

No. 796,307.

Specification of Letters Patent.

Patented Aug. 1, 1905.

Application filed July 1, 1904. Serial No. 214,990.

To all whom it may concern:

Be it known that we, CHARLES P. FAY and OSCAR F. MOSSBERG, citizens of the United States of America, residing at Chicopee Falls, in the county of Hampden and State of Massachusetts, have invented new and useful Improvements in Breech-Loading Firearms, of which the following is a specification.

This invention relates to breech-loading firearms, and has especial reference to that type of firearms in which the breech mechanism comprises a longitudinally and rotatably movable bolt having an axially-movable hammer therein, the object of the present invention being to provide a breech-closing mechanism of this type in which when the bolt is moved forward to close the breech the hammer will be momentarily arrested toward the end of the breech-closing movement of the bolt, then allowed to advance after the bolt has been locked, whereby when the end of the bolt comes in contact with the cartridge the end of the firing-pin will be retracted, thus preventing a possible premature explosion should the bolt be shot forward quickly.

A further object of the invention consists in the construction of a breech-closing mechanism and receiver, comprising means to effect the locking of the bolt non-rotatably in the receiver by the cocking movement of the hammer.

A further object of the invention is to provide a breech mechanism which may be dismounted without tools and in which a loosely-mounted extractor constitutes a locking means to hold the parts normally in operative position in the receiver.

The invention is clearly illustrated in the accompanying drawings, in which—

Figure 1 is a sectional elevation of the receiver of a firearm in which this invention has been embodied, a portion of the barrel being shown in elevation. Fig. 2 is an end elevation of the same. Fig. 3 is a view similar to Fig. 1, showing the breech mechanism partly in section in an open position. Fig. 4 is a side elevation of the bolt and hammer, showing the position of the parts at the beginning of the rotatable movement of the bolt, whereby the latter is secured in breech-closing position, the receiver being outlined in dotted lines. Fig. 5 is an end elevation of the parts

shown in Fig. 4. Fig. 6 is a view of the parts shown in Fig. 4 after the bolt has been rotated, the receiver being shown in full lines in longitudinal section and the hammer being shown in cocked position in dotted lines. Fig. 7 is an end elevation of the bolt with the parts in position shown in Fig. 6. Fig. 8 is a vertical section on line 8-8, Fig. 6.

Referring now to the drawings, *a* indicates the barrel, and *b* the receiver or frame, of the firearm in which the breech mechanism is mounted. This breech mechanism consists of a bolt *c*, bored out axially to receive the spring-operated plunger *d*, to the outer end of which is secured the head *e* in any suitable manner. The inner end of the plunger *d* is also provided with a head, between which and the outer end of the bolt the plunger is encircled by a coiled spring *g*, which is the mainspring and is compressed when the head *e* is drawn out.

In the forward end of the bolt *c* a loose firing-pin *h* is mounted in any suitable manner, the rear end of which extends into the axial recess in the bolt, in which said plunger *d* moves, and is so arranged that the head of plunger will strike it at the moment of firing and effect the ignition of the cartridge in the usual manner.

The trigger *j* is hung on the under side of the receiver at *k*, and *k'* indicates a spring-actuated plunger constituting the trigger-spring.

The under side of the bolt is cut away, whereby an opening *m* is provided extending into the axial recess in which the plunger *d* is located. Into this recess the nose *o* of the trigger extends, as well as the upturned rear end *p* of the extractor *q*, which is provided with a hooked forward end to engage the rim of the cartridge in the usual manner, and it is moved forward by the engagement of the bolt with the hooked end thereof and retracted by the engagement of the upturned end *p* thereof with the under side of the bolt when the latter moves in the opposite direction.

A spring *r* is so located that when the extractor is in position to engage the head of a cartridge this spring, bearing against the under side of the extractor, will be compressed, and it is so arranged as to hold the hook end of the extractor against the cartridge during

the beginning of the breech-opening movement of the bolt *c*, this position being shown in Fig. 6.

The plunger *d* and the head *e*, as stated, constitute practically one piece, and there is let into the head *e* a flat tongue *s*, which extends forward under the bolt and has a sliding movement on the latter in the flat groove *t*. This tongue *s* is made of hardened steel, and, as shown in Fig. 6, the end thereof is engaged by the nose of the trigger when the head *e* is pulled back to cocked position. This construction so unites the head *e* and the bolt *c* that they are rotatable together, means to rotate the bolt being provided in the lever *v*. As stated, however, the head is movable longitudinally independently of the bolt.

The tongue *s* when the hand-lever *v* is in a vertical position will be located in one side of the receiver, the bolt thus presenting a smooth under surface to the trigger, whereby the forward-and-backward movement of the bolt will be unobstructed; but when the bolt is moved forward far enough to bring the lever *v* in position to be swung laterally down past the shoulder *w* in the receiver and has been so rotated to lock the bolt against retraction the flat tongue *s* will be swung down to position directly over the trigger, as shown in Figs. 6 and 8, and when the head *e* is pulled out the nose of the trigger will engage in the forward end of said tongue, thus holding the hammer in cocked position.

It will be observed that on the side of the head *e*, near the forward edge thereof, is a short stud *x* and that in the wall of the receiver, at the rear end thereof, are two parallel grooves 3 and 4, which run into an inclined groove 5, also in the wall of the receiver and of substantially the same depth as the grooves 3 and 4. These grooves 3, 4, and 5 receive the stud *x* on the head *e*.

When the bolt is pushed forward to lock the breech of the barrel, the stud *x* travels in the groove 3, and just before the end of the bolt reaches the limit of its movement this stud will come to a bearing against the wall of the groove 5 lying opposite the end of the groove 3, which will prevent further movement of the head endwise with the bolt. Continued movement of the latter will bring the parts to the position shown in Fig. 4—that is, the bolt *c* will advance independently of the head and push the cartridge to its seat in the barrel, the degree of this movement of the bolt relative to the head *e* being shown by the space 6, which separates these parts, (see Fig. 4,) and this separation of the bolt and head *e* effects a like separation between the forward end of the plunger *d* and the rear end of the firing-pin 8, this separation being indicated at 7, Fig. 4, and obviously is the same in degree as the separation between the bolt and the head *e*. When the bolt is in the position shown in Fig. 4, it may be rotated by throwing

the lever *v* to the right and down back of the shoulder *w* on the receiver, this rotation causing the stud *x* on the head *e* to move down the groove 5 in the wall of the receiver, whereupon the spring *g* will move the head *e* and the plunger *d* forwardly, as permitted by the forward inclination of said slot, the end of the plunger *d* thus being allowed to move slowly forward into contact with the firing-pin. If now the head *e* and the plunger *d* be pulled out to cocked position, it will be observed that the stud *x* will slide rearwardly in the groove 4, and when the hammer is cocked the stud will remain in said groove. Therefore as the head *e* is non-rotatably connected with the bolt *c* the latter will be locked against rotation in the manner described when the hammer is cocked.

A novel feature of this invention consists in the assemblage of the parts in operative position in the receiver, whereby while securely locked therein they may be removed without the use of tools, the extractor constituting a key to effect such locking.

To remove the bolt *c*, the parts are moved to the position shown in Fig. 3, and the trigger is pulled back far enough to depress the nose *o* thereof to the position indicated in dotted lines in said figure, whereupon the extractor will slide over the nose of the trigger, dropping down far enough to effect its disengagement with the shoulder which constitutes the forward end of the opening *m*, whereupon the bolt may be pulled out of the receiver. It is clear, however, that as long as the trigger remains in the position shown in Fig. 3 the upstanding end *p* of the extractor will always be caught between the bolt and the trigger when the bolt is pulled out.

It is of course obvious that the operation of the hereinbefore-described hammer and firing-pin would be the same in all respects if the firing-pin *h* and the plunger *d* were made in one piece, and any such change as this would fall within the scope of the invention. In the claims, therefore, the word "hammer" may be used to signify the mechanism comprising the firing-pin *h*, the plunger *d*, and the head *e*, as these, in effect, constitute the hammer.

Having thus described our invention, what we claim, and desire to secure by Letters Patent of the United States, is—

1. In a firearm comprising a bolt and a hammer movable endwise therewith and therein, means to arrest the movement of the hammer near the end of the forward movement of the bolt, and means, actuated by the rotatory movement of the bolt, to effect the gradual advance of the hammer into contact with the primer of the cartridge.

2. In a firearm comprising a frame, a bolt, a hammer in the bolt endwise movable therein and therewith, there being an abutment on the frame to temporarily interrupt the for-

ward movement of the hammer when the bolt is moved forward, together with means operable by the rotative movement of the bolt, to release the hammer from said abutment.

3. A breech mechanism for a firearm comprising a bolt and a hammer therein, means to restrain the forward movement of the hammer during a portion of the movement of the bolt in one plane toward the cartridge, and means, operable by the rotation of the bolt, to effect the disengagement of the hammer from said restraining means.

4. In a breech-loading mechanism of the character described, a suitable frame, a bolt, a hammer, one end of which constitutes a continuation of the bolt, a tongue extending from said end of the hammer into a groove or recess in the bolt; a stud in said end of the hammer to enter a groove in the frame when the bolt moves forward, there being a second groove in the frame into which said stud is moved when the hammer is drawn back to cocked position, whereby the bolt is locked against rotation at that time.

5. The combination in a firearm of the character described, of a bolt and a hammer, endwise movable as one piece, and means operable during the forward movement of the bolt to hold back the hammer at the moment of contact of the bolt with a cartridge, together with means actuated by the rotatory movement of the bolt to effect the slow advance of the hammer to a position of contact with the cartridges.

6. In a firearm of the character described, a suitable frame, a bolt, a hammer endwise movable therein and non-rotatable relative thereto, one end of the hammer constituting a continuation of the bolt; a stud in the side of the last-named portion of the hammer, there being two parallel grooves in the frame through one of which said stud moves during the breech-closing movement of the bolt, and through the other of which said stud moves when the hammer is cocked, there being a third groove in the frame intersecting one end of said parallel grooves, through which said stud moves when the bolt is rotated; the wall of said third groove constituting a stop to arrest the forward movement of the hammer at some point during the like movement of the bolt.

7. In a firearm of the character described, a suitable frame, an endwise-movable bolt therein, an endwise-movable hammer in the bolt, there being an inclined groove in the frame, with the wall of which a projection on the hammer engages during the forward movement of the bolt, to permit the latter to move independently near the end of its forward movement, said inclined groove serving to permit further forward movement to the hammer, when the bolt is rotated.

8. In a firearm of the character described, a suitable frame, an endwise-movable bolt in the frame, an endwise-movable hammer in the bolt, the latter and said hammer being rotatable as one piece; means to lock the hammer against rotation when it is drawn out into cocking position, whereby the bolt is likewise locked against rotation.

9. In a breech-loading firearm of the character described, a suitable frame, a bolt movable toward and from the rear end of the barrel, an extractor located between the under side of the bolt and the frame, slideable with the bolt in opposite directions in a groove in the frame, and a spring in said groove to hold the hooked end of the extractor in engagement with the head of a cartridge, during the operative movement of the extractor.

10. In a firearm of the character described, the combination with a suitable frame, of a trigger pivotally supported thereon, the nose of the trigger extending through an opening in the bottom of the frame; an endwise-movable bolt in the frame, there being a recess in the bolt registering with the opening in the frame when the bolt is retracted; an extractor having an upturned rear end, the latter and the nose of the trigger extending into said recess in the bolt, whereby the nose on the trigger constitutes an abutment to limit the rearward movement of the bolt, said upturned end of the extractor, located between the end of the recess in the bolt and the nose of the trigger, constituting a locking means for the bolt.
